UNITED STATES PATENT OFFICE

GEORGE DE MAZIROFF, OF NEW YORK, N. Y., ASSIGNOR TO NATIONAL AUTOMATIC CONTAINER CORPORATION, OF BALTIMORE, MARYLAND, A CORPORATION OF MARYLAND

CIGARETTE PACKAGE CONTAINER

Application filed August 22, 1930, Serial No. 477,025. Renewed February 24, 1932.

This invention relates to improvements in cigarette package containers, particularly that type of container adapted to hold the usual paper or tin foil pack of cigarettes, and 5 is an improvement in part on my copending application Ser. No. 412,387 filed December 7, 1929.

An object of this invention is to provide 10 a device adapted to slice the top of a pack of cigarettes for part of its length automatically and also destroy the revenue stamp thereon as the pack is placed therein.

Another object is to provide a cigarette 15 container wherein the loose flap formed by slicing the top of the pack as it is placed in the container, is automatically disposed in such position in the container that it does not interfere with the removal of cigarettes from the container.

20 Another object is to provide a blade particularly adapted for slicing the top of a pack of cigarettes and a holder therefor from which the blade may easily be removed and replaced. A further object is to provide 25 means whereby cigarettes may be easily removed from the device.

A further object of the invention is to provide 30 a container which will protect the cigarettes from crushing regardless of whether the pack is full or nearly empty.

The device of this invention is one adapted 35 to hold a pack of cigarettes and comprises a container, preferably of metal, of substantially the same shape as the pack to be held, having one end and a portion of the top adjacent its opposite end open, a movable cover adapted to close the opening in the top of the container, and a blade adapted to lie parallel 40 to the top of said container and present its cutting edge toward the open end of the container, said blade being spaced sufficiently below the top of the container so that it is adapted to engage the pack of cigarettes 45 slightly below the top thereof and slice the top thereof upon relative movement of the blade and pack.

More specifically, the top of the container 50 is open except for a narrow top wall adjacent its open end and the cover is hinged to the inner edge of the top wall. The cover is pro-

vided with depending side walls and a blade holder is carried by said side walls and spaced from the top of the cover. This blade holder carries a readily removable blade, preferably comprising a flat piece of 55 metal having a substantially rectangular unsharpened pack portion adapted to fit in the holder, a front cutting portion formed into a pair of apexes and side cutting edges extending parallel to each other for a portion 60 of their length and then sloping inwardly to form the outer cutting edges of apexes. A thumb hole is provided in the bottom of the container opposite the open part thereof to facilitate removal of cigarettes from the inserted pack.

To understand the invention more fully, reference is made to the accompanying drawings in which:

Fig. 1 is a longitudinal section of a cigarette package container embodying the invention showing a pack of cigarettes partially inserted and the cover of the container closed.

Fig. 2 is a section taken on the line 2—2 of Fig. 1 in the direction of the arrows.

Fig. 3 is a longitudinal section of the container shown in Fig. 1 with the pack of cigarettes fully inserted and the cover raised.

Fig. 4 is a section taken on the line 4—4 of Fig. 3.

Fig. 5 is a top plan view illustrating the preferred form of blade to be used in the container.

Fig. 6 is a bottom plan view.

The device illustrated comprises a substantially rectangular container, preferably made of metal, having side walls 1, a single end wall 2, bottom 3, and the narrow top wall 4 extending only a short distance from the open end of the container. The side walls 1 and end wall 2 are preferably cut away at their centers to leave merely a margin of sufficient width to assure a rigid structure as shown in the drawings. Also, the side walls 1 and top wall 4 are beaded adjacent the open end of the container, the beading indicated by reference numeral 6. The bottom of this container is approximately the width of the pack of cigarettes to be held, designated by reference numeral 10, and the top is slightly 100

wider. For example, the width of the usual pack of cigarettes is 14/16 of an inch and the container to hold these packs is preferably made 14/16 of an inch in width at the bottom and one inch in width at the top. The pack 10 is inserted in the open end of the container as shown in Fig. 1.

A cover 11, adapted to close the open portion of the top of the container and having depending side walls 12 and an end wall 13, is hingedly connected to the top wall 4 of the container along its inner edge. This cover is preferably provided with spring means to swing it into open position, no such means being shown in the drawings as it does not form part of the present invention and may be of any conventional design. To hold the cover shut against such spring action or an accidental jolt, the end wall 13 of the cover is provided with projection 14 adapted to engage a similar projection 15 on the end wall 2 of the container. The wall 2 is stamped out to form a knob 18 which may be pushed to release the cover.

Disposed in the cover 11 is a blade holder 25 consisting of a piece of metal doubled back on itself and soldered to the side walls 12 of the cover parallel to but spaced from the top of the cover 11. This blade holder frictionally holds the blade 26, the holder being indented at 28 and a hole 29 being provided in the blade 26 to cooperate therewith to more securely hold the blade.

As is clearly shown in Figs. 1 and 3 the blade is held in position parallel to but spaced below the top of the cover 11 and presents its cutting edge, when the cover is closed, toward the open end of the container, the blade extending to about the inner edge of cover 11. In use, a pack of cigarettes is inserted in the open end of the container with the cover closed and pushed all the way in. The blade 26 is positioned to engage the pack above the cigarettes and slits the top as the pack is pushed in, the cut portion of the top of the pack going between the blade and the top of the cover. After the pack is inserted, the cover 11 is swung up, carrying with it the slit part of the pack and exposing the cigarettes as shown in Fig. 2. A thumb hole 30 is provided in the bottom 3 of the container opposite the open part of the top so that the cigarettes may be easily pushed out.

The blade 26 shown in the drawings is particularly suited for use in the present device. It consists of a flat piece of metal having a substantially rectangular back portion 40 which is not sharpened and is adapted to be inserted in the blade holder 25 and abut against the rear of the holder as shown in Figs. 1 and 3. The blade has a front cutting portion formed into a pair of apexes 41 and 42 and side cutting edges 43 and 44 extending parallel to each other and at right angles 65 to the back edge for a portion of their length

and then sloping inwardly at 45 and 46 to form the outer cutting edges of the apexes 41 and 42, respectively. Preferably the blade is curved slightly at 45 and 46, it being found that the top of the pack of cigarettes is cut more smoothly when the blade is rounded at these points rather than brought to a definite angle. The blade is provided with a second hole 48 which is not covered by the holder 25, the purpose of the hole 48 being to facilitate removal of the blade by inserting a pin or knife point in the hole.

The blade shown in the drawings is especially advantageous for this purpose as the two apexes pierce the pack and the sides of the pack adjacent its top are smoothly cut by the outside edges of the blade. The blade, except for the base 40, is made slightly less in width than the cover but wider than the pack to be cut. In a container for holding the usual size packs of cigarettes the base of the blade is made a shade less than one inch in width to seat surely in the holder, the cover being one inch in width, and the maximum width of the cutting edge of the blade is made 15/16 of an inch so as to exceed the width of the pack by 1/32 of an inch on each side and leaving a space of 1/32 of an inch between the blade and side wall 12 of the container at the point of maximum width of the cutting edge. When the blade becomes dull it can be removed and sharpened or replaced by a new blade.

To accurately guide the pack of cigarettes as it is being inserted, the side walls are provided on the inside with ridges 32 which flatten out at the open end of the container. The corners 33 of the container adjacent its closed end are extended somewhat above the walls of the container to guide the cover 11 to its proper closed position and also to hold it more securely in that position.

The invention claimed is:

1. A device adapted to hold a pack of cigarettes comprising a container of substantially the same shape as the pack to be held, having one end and a portion of the top adjacent the opposite end thereof open, a movable cover adapted to close the opening in the top of the container, a blade holder carried by said cover and arranged to frictionally hold a blade parallel to and slightly below the top of said container, and a removable blade disposed in said holder and presenting its cutting edge toward the open end of said container whereby the top of the pack is sliced upon relative movement of the pack and the blade.

2. A device adapted to hold a pack of cigarettes comprising a container of substantially the same shape as the pack to be held, having one end and a portion of the top adjacent the opposite end thereof open, a movable cover adapted to close the opening in the top of the container, a blade holder carried by said

cover and arranged to frictionally hold a blade parallel to and slightly below the top of said container, and a removable blade disposed in said holder, said blade comprising a flat piece of metal having an unsharpened back portion adapted to fit in the blade holder and a front portion having cutting edges along the sides and front thereof.

3. A device adapted to hold a pack of cigarettes comprising a container of substantially the same shape as the pack to be held, having one end and a portion of the top adjacent the opposite end thereof open, a movable cover adapted to close the opening in the top of the container, a blade holder carried by said cover and arranged to frictionally hold a blade parallel to and slightly below the top of said container, and a removable blade disposed in said holder, said blade comprising a flat piece of metal having an unsharpened back portion adapted to fit in the blade holder and a front portion having cutting edges along the sides and front thereof, the front portion of said blade being adapted to extend beyond the blade holder and being provided with a hole therein to facilitate removal of the blade by a pointed instrument.

4. A device adapted to hold a pack of cigarettes comprising a container of substantially the same shape as the pack to be held, having one end and a portion of the top adjacent the opposite end thereof open, a movable cover adapted to close the opening in the top of the container, a blade holder carried by said cover and arranged to frictionally hold a blade parallel to and slightly below the top of said container, and a removable blade disposed in said holder, said blade comprising a flat piece of metal having an unsharpened back edge adapted to abut against the rear of the blade holder and a front cutting portion formed into a pair of apexes and side cutting edges extending parallel to each other for a portion of their length and then sloping inwardly to form the outer cutting edges of the apexes.

5. A device adapted to hold a pack of cigarettes comprising a container of substantially the same shape as the pack to be held, having one end and a portion of the top adjacent the opposite end thereof open, a movable cover adapted to close the opening in the top of the container, side walls carried by said cover, a blade holder comprising a piece of metal doubled on itself attached to said walls and spaced from the top of said cover and arranged to frictionally hold a blade parallel to and spaced from the top of the cover, and a blade disposed in said holder and presenting its cutting edge toward the open end of said container whereby the top of the pack is cut upon relative movement of the pack and blade.

6. A device adapted to hold a pack of cigarettes comprising a container having a bot-

tom substantially the same shape and size as the bottom of the pack of cigarettes to be held and a top 2/16 of an inch wider than the bottom, said container having one end and a major portion of the top adjacent the opposite end open, a rectangular cover hingedly attached to the top and adapted in closed position to lie parallel to said top and close the opening therein, depending side walls carried by said cover, a blade holder attached to said walls and spaced from the top of the cover and arranged to frictionally hold a blade parallel to and spaced from the top of the cover, and a removable blade 1/16 of an inch wider than the bottom of the container disposed in said holder and adapted to engage the pack of cigarettes slightly below the top thereof and cut the top as the pack is inserted through the open end of the container.

7. A device adapted to hold a pack of cigarettes comprising a container of substantially the same shape as the pack to be held, having one end and a portion of the top adjacent the opposite end thereof open, a movable cover attached to the top and adapted in closed position to lie parallel to said top and close the opening therein, depending side walls carried by said cover, a blade holder attached to said walls and spaced from the top of the cover and arranged to frictionally hold a blade parallel to and spaced from the top of the cover, and a removable blade disposed in said holder and adapted to engage the pack of cigarettes slightly below the top thereof and cut the top as the pack is inserted through the open end of the container.

8. A device adapted to hold a pack of cigarettes comprising a container of substantially the same shape as the pack to be held, having one end and a major portion of the top adjacent the opposite end thereof open, a cover hinged to the top and adapted in closed position to lie parallel to said top and close the opening therein, depending side walls carried by said cover, a blade holder comprising a piece of metal doubled on itself attached to said side walls and spaced from the top of the cover, said holder being arranged to frictionally hold a blade parallel to and spaced from the top of the cover, and a removable blade disposed in said holder and adapted to engage the pack of cigarettes slightly below the top thereof and cut the top as the pack is inserted through the open end of the container.

9. A device adapted to hold a pack of cigarettes comprising a container of substantially the same shape as the pack to be held, having one end and a major portion of the top adjacent the opposite end thereof open, a cover hinged to the top and adapted in closed position to lie parallel to said top and close the opening therein, depending side walls carried by said cover, a blade holder comprising a piece of metal doubled on itself

- attached to said side walls and spaced from the top of the cover, said holder being arranged to frictionally hold a blade parallel to and spaced from the top of the cover, and a 5 removable blade disposed in said holder and arranged to engage the pack of cigarettes slightly below the top thereof and cut the top as the pack is inserted through the open end of the container, said blade holder being 10 provided with an indentation and said blade being provided with a hole adapted to cooperate with said indentation to hold the blade securely.
10. A device adapted to hold a pack of cigarettes comprising a container of substantial- 15 ly the same shape as the pack to be held, having one end open to admit the pack and a portion of the top adjacent the opposite end open to permit the cigarettes to be removed, and 20 a blade spaced from the top of the container having a front cutting edge toward the open end of the container and side cutting edges substantially parallel to each other for at least a portion of their length.
- 25 11. A device adapted to hold a pack of cigarettes comprising a container of substantially the same shape as the pack to be held, having one end open to admit the pack and a portion of the top adjacent the opposite end 30 open to permit the cigarettes to be removed, and a blade spaced from the top of the container having a front cutting edge toward the open end of the container and side cutting edges substantially parallel to each other and 35 further apart than the width of the pack to be cut.
12. A device adapted to hold a pack of cigarettes comprising a container of substan- 40 tially the same shape as the pack to be held, having one end open to admit the pack and a portion of the top adjacent the opposite end open to permit the cigarettes to be removed, a movable cover adapted to close the opening in the top of the container, and a blade 45 secured to and spaced slightly from said cover having a front cutting edge toward the open end of the container and side cutting edges substantially parallel to each other and spaced from the edges of said cover.
- 50 Signed at New York, in the county of New York and State of New York, this 21st day of August, A. D. 1930.

GEORGE DE MAZIROFF.
